FOUNTAIN PENS

Albert E. Simon, Jr., Glenside, and Richard J. Cavaliere, Philadelphia, Pa., assignors to The Esterbrook Pen Company, Camden, N.J., a corporation of New Jersey
Filed May 28, 1958, Ser. No. 738,406
3 Claims. (Cl. 120—45.4)

This invention relates to fountain pens and to that type of such structures employing capsules or cartridges containing fluid ink.

In fountain pens of this type, the barrel contains a cartridge (or cartridges) filled with ink which is to be placed in communication with the writing assembly of the fountain pen whereby writing can be effected through use of the ink originally contained in such cartridge (or cartridges). Initially these cartridges comprise sealed containers which may be made of any suitable material, preferably and usually a plastic body more or less transparent or translucent such as polyethylene or the like and they have sealed delivery ends which must be pierced or ruptured in order that the ink contained therein may flow therefrom. The sealed ends usually include an integral thin-walled web or diaphragm which is pierced by suitable means; usually a tubular cutting element which, in addition, affords a conduit for the passage of ink from the cartridge.

Many attempts have been made to develop fountain pens of this type with satisfactory piercing means for operation upon the cartridge closure; such means being disposed between the cartridge and the writing assembly comprising the nib and feed-bar whereby after proper disposal of the cartridge within the fountain pen barrel and rupture of its closure, there will be delivery of ink from the cartridge to the nib and feed-bar, and provision for the ingress of air to replace the ink consumed.

The main object of the present invention is to employ means, including what has come to be known as a "Renew-Point" unit, later described, in one form, that will place the writing assembly comprising the nib and feed-bar of such "Renew-Point" unit in communication with the ink contained within the cartridge. This "Renew-Point" unit has been successfully employed with fountain pens of usual type, that is to say, those having a sac for the reception of an ink supply or those which utilize the barrel as the reservoir. But the arrangements or constructions heretofore employed are not directly available for use with fluid ink cartridges closed by a puncturable diaphragm which must be ruptured in order that the ink contents may flow continuously and uninterruptedly to the writing assembly during a writing operation.

For the purpose of insuring proper flow of ink from the cartridge and ingress of air to replace the ink consumed, means have been provided that lie within the section of the fountain pen just behind the "Renew-Point" unit; such means carrying a tubular piercing element which, after rupturing the cartridge diaphragm when the parts are assembled, will serve for the conveyance of ink through its bore. These means comprise a body member carrying the tubular cutting element at its upper end and being disposed with its lower end in relatively close engagement with the rear end of the "Renew-Point" unit. This end of the body member is provided with what may be termed a cross feed; comprising slots of proper dimensions providing capillary channels for the passage of ink and air.

The terms "upper" and "lower" as used above are purely relative and indicate the position of the feed member when the fountain pen is being used in a writing operation, as illustrated in FIGS. 1 and 2.

The lower end of the body member is faced or shaped

2

in a particular manner in order to provide a capillary space for the reception of ink from the bore of the tubular cutting element, which ink covers substantially the entire surface at the end of the writing assembly unit.

5 This surface of the body member has a rib or raised portion concentrically arranged and in relative contact with the surface of the "Renew-Point" unit carrying the writing assembly. Surrounding this annular rib or raised portion are sloping surfaces, inwardly and outwardly 10 thereof, and their presence provide the desired capillary space for the reception of ink. This conformation is of importance since, as the body member is relatively loosely held in the section of the fountain pen, there is some possibility of its canting slightly when the parts are assembled. This canting, if present, will not affect the 15 capillarity of the space which is, at all times of use during a writing operation, filled with ink. The cross slots of the body member cut across or through its central bore and provide channels of capillary dimensions for the 20 passage of ink and air from and to such central bore; the ink channel being rather deep and narrower than the air channel which is shallow and wider than the ink channel. The body member is of two diameters externally and the upper portion, of less diameter, receives 25 a washer or gasket lying between it and the wall of the section to insure that no ink from the space above referred to will pass such member.

In the present instance the improved ink feeding means have been shown in connection with a barrel containing 30 two cartridges arranged with their rear ends in abutting relation. It will be understood that a single cartridge may be employed which will be of greater length longitudinally of the barrel.

The end of the barrel is provided with a sleeve, which 35 may be of metal, and may be frictionally held therein; such sleeve having a projecting portion which is internally and externally threaded; the internal threads receiving the pen section and the external threads receiving the cap of the fountain pen. After the pen section 40 is removed, the cartridge (or cartridges) may be dropped into the barrel and then, when the section carrying the ink-feeding means with the tubular piercing element is screwed into place, the tubular piercing element penetrates the diaphragm of the cartridge and the contents 45 thereof are then free to flow through the ink-feeding member and thence to the writing assembly. When two cartridges are employed and the forward cartridge has dispensed its ink contents, the parts may be separated by unscrewing the section from the connecting sleeve and 50 the fresh cartridge may be set forward; the used cartridge being placed in the barrel behind the same. Then, when the section is screwed home, the tubular cutting element will pierce the diaphragm and ink will flow from the cartridge. When not in use, the fountain pen should be 55 carried in the pocket with the point section in the upper position.

These and other features of the invention are more fully described hereinafter; reference being had to the accompanying drawings, more or less diagrammatic in 60 character, in which:

FIGURE 1 is a longitudinal view of a fountain pen; a portion of the same being broken away to illustrate the features of the present invention; the section being on the same plane as FIG. 2.

FIG. 2 is an enlarged sectional view of the parts constituting the subject of the present invention and which lie between the "Renew-Point" unit and the cartridge; the section being on the line II—II, FIG. 3.

FIG. 3 is a cross sectional view on the line III—III, FIG. 2.

FIG. 4 is a cross sectional view on the line IV—IV, FIG. 2, and

FIG. 5 is an exploded perspective view of the parts forming the subject of the present invention.

In the drawings, the barrel of the fountain pen is indicated at 10 and receives at its forward end a tubular extension 11, which may be of metal and may be frictionally held in tight engagement with the barrel, such extension projecting forwardly of the barrel and being threaded internally at 11^a, and externally at 11^b. Disposed in engagement with the internal threads 11^a of the extension 11, is the section 12 of the fountain pen which receives at its outer end the writing assembly comprising a nib 13 and a feed-bar 14; the latter having ink channels 14^a and an air channel 14^b, and such parts being fixedly mounted in a sleeve 15. This sleeve, with the contained nib and feed-bar, constitutes the "Renew-Point" unit which is in threaded engagement, as indicated at 12^a, with the outer end of the section 12. In the usual arrangement, in the mounting of such "Renew-Point" unit in a fountain pen, the rear end of the sleeve, such as 15, abuts a seat—preferably beveled—within the section 12, and the same arrangement is found in the present assembly of the parts; the beveled seat being indicated at 12^b. The external threads 11^b of the extension 11 receives the cap of the fountain pen.

In the present instance, the barrel of the fountain pen is designed to receive two cartridges containing fluid ink with their rear ends in abutting relation and their dimension is such as to permit ready insertion and removal. In the present instance, the forward cartridge is shown partly in section in FIGS. 1 and 2. These cartridges may be made of any suitable plastic, which may be transparent or translucent; preferably of polyethylene, and they are more or less resilient so as to be retained in proper relation within the barrel of the fountain pen.

The forward end of the cartridge indicated at 16 and shown in FIGURES 1 and 2 in the lower position, is provided with a recess 16^a which may function as a bore; having an outwardly flaring or tapered mouth, the inner end of such recess 16^a being closed by a thin-walled puncturable web or diaphragm 16^b which, when pierced or ruptured, permits the ink to flow from such cartridge. The cartridge not in use lies with its puncturable end in contact with the inner rear wall of the barrel; the rear ends of such cartridges lying in abutting relation.

Between the inner end of the feed-bar 14 carried by the sleeve 15 of the "Renew-Point" unit and the diaphragm end of the cartridge 16, the cooperative means providing for proper feed of ink from the cartridge to the writing assembly and forming the subject of this invention is mounted.

The cooperative ink-feeding means include a body member 20, more or less loosely mounted for axial shifting movement during its assembly in the section 12 behind the "Renew-Point" unit, and its upper portion, indicated at 20^a, is of less diameter than the main body. In the space between the outer surface of such upper reduced portion and the inner wall of the section 12, an elastic gasket or washer 21 is disposed to prevent leakage of ink around the body member 20. To provide an abutment for engagement by the diaphragm end of the cartridge, the reduced end portion 20^a of the body member may carry a disc 22, which may be of any suitable stiff material; preferably metal.

The body member is axially bored, and such bore is of two diameters. The upper and larger bore portion receives a tubular cutting element 23, frictionally and tightly held therein, such cutting element having a tapered or beveled cutting edge portion 23^a.

Within the bore of the cutting element 23 a rod 24, grooved at 24^a throughout its length and cut away at one side as indicated at 24^b, is mounted, such construction providing a longitudinal space 24^c adjacent to the inner wall of the bore of the tubular cutting element 23, and such groove and space provide capillary channels for the

passage of ink to the lower end of the same and for the ingress of air as the ink is consumed.

The rod 24, disposed within the bore of the tubular cutting element 23, has a relatively close fit therewith at its upper end, such tubular cutting element being disposed in the axial bore of the body member 20 and terminating near the upper end of such bore. Below this point an annular space 20^b is provided between the wall of the bore and the rod 24, and such space is of capillary size and will draw ink from the capillary space provided by the flat side of the rod 24 and the inner wall of the cutting element and the bore of the body member 20. Since a complete ring of ink is provided by this annular space, ink will be delivered to the adjacent cross feed slots (hereinafter referred to) regardless of the actual orientation of the two parts.

The complete ring of ink in the annular space 20^b above referred to will cut off the flow of ink to the longitudinal space 24^c adjacent to the air slot of the rod 24. Thus a hydrostatic lock is formed which prevents siphoning. When ink is drawn from the pen during a writing operation, it is first drawn from the longitudinal space 24^c adjacent to the air slot of the rod 24 (since it has the least capillary strength) and intermittent air bubbles are permitted to enter the cartridge.

The lower end of the body member 20, which lies in a substantially single plane at right angles to its longitudinal axis, is cross slotted as indicated at 26 and 27 for the passage of ink and air from and to its bore. The slot 26 is deeper than the slot 27, but narrower and forms a capillary channel for the passage of ink from the space 20^b, while the slot 27 is wider than slot 26 and forms a capillary channel for the passage of air as the ink is consumed. The extreme lower end of the member 20 is formed with an annular projection 25 with sloping faces 25^a and 25^b, inwardly and outwardly thereof and concentrically disposed with respect to the outer contour of said member. This annular projection of the body member 20 lies in contact with the inner end of the feed-bar 40 of the "Renew-Point" unit, and the spaces provided by the sloping faces 25^a and 25^b will fill with ink and insure passage thereof to the ink and air channels of the feed-bar. It will be noted that by virtue of said sloping faces, the "spaces" defined thereby have varying degrees of capillarity.

When a cartridge is in position, insertion of the "Renew-Point" unit and complete seating of the same against the seat 12^b will press against the body member, imparting slight movement to the same longitudinally within the section 12 and will cause the tubular cutting element to rupture the diaphragm and place its bore in communication with the body of ink within the cartridge; the displaced portion of the diaphragm being pushed to one side as the rupture is completed, as indicated in FIGS. 1 and 2. Following assembly as aforesaid, the body member 20 is biased into effective engagement with the inner end of the feed-bar 15 by the tendency of the cartridge to expand axially.

In operation, after the diaphragm has been ruptured, ink will flow from the cartridge to the bore of the body member and the cross-slot 26 and thence to one of the capillary channels of the feed-bar, while air will enter the other channel and pass via the cross-slot 27 and the air passage in the bore of the tubular cutting element; entering the cartridge to replace the ink flowing therefrom.

FIG. 1 shows the fountain pen in the position of use, and in the operation of writing, the ink and air will flow simultaneously in opposite directions.

It may be desirable, at times, to remove the body member and wash the same in water; thereby removing any sediment that may collect from the ink that has been used.

While certain features of this invention are shown in the drawings and described in the specification with some

degree of specific construction; such illustration and description are for illustrative purposes only and not as limiting the invention in any manner since modification and changes may be made within the spirit thereof; all of which is deemed to be within the scope of the appended claims.

We claim:

1. In a fountain pen, the combination of a barrel, a writing assembly comprising a nib, a feed-bar having channels for the passage of ink and air and a sleeve in which said nib and feed-bar are permanently mounted to function as a unit detachably mounted in the end of the barrel, an ink-containing cartridge having a rupturable diaphragm sealing one end and disposed in the barrel opposite the writing assembly unit, and an ink-feeding assembly interposed between the writing assembly unit and the delivery end of the cartridge; said ink-feeding assembly comprising a body member having a through bore in axial alignment with the cartridge, a tubular cutting element mounted in the bore of said body member and adapted to pierce the diaphragm of the cartridge when the parts are assembled, and provision within the bore of said cutting element for the passage of ink and air.

2. In a fountain pen, the combination of a barrel, a section mounted at the forward end of said barrel, a writing assembly comprising a nib, a feed-bar having channels for the passage of ink and air and a sleeve in which said nib and feed-bar are permanently mounted to function as a unit detachably mounted in the end of said section, an ink-containing cartridge having a rupturable diaphragm sealing one end and disposed in the barrel opposite the writing assembly, and an ink-feeding assembly operatively interposed between and engaged with the cartridge and the writing assembly and mounted therein

for limited axial shifting movement within the barrel during assembly of said parts and being biased into engagement with the feed bar by said cartridge; said ink-feeding assembly comprising a body member having a through bore in axial alignment with the cartridge, a tubular cutting element mounted in the bore of said body member and adapted to pierce the diaphragm of the cartridge when the parts are assembled, and provision within the bore of said cutting element for the passage of ink and air.

3. In a fountain pen, the combination of a barrel, a writing assembly comprising a nib, a feed-bar having channels for the passage of ink and air and a sleeve in which said nib and feed-bar are permanently mounted to function as a unit detachably mounted in the end of the barrel, an ink-containing cartridge having a rupturable diaphragm sealing one end and disposed in the barrel opposite the writing assembly unit, and an ink-feeding assembly interposed between the writing assembly and the delivery end of the cartridge; said ink-feeding assembly comprising a body member having a through bore in axial alignment with the cartridge, a tubular cutting element carried by and disposed in the bore of said body member and adapted to pierce the diaphragm of the cartridge when the parts are assembled, means arranged within the bore of said cutting element defining capillary channels for the passage of ink and air; the end of said body member being provided with an annular ridge having portions sloping inwardly and outwardly to define ink receiving spaces between the body member and the writing assembly unit and having at such end slots of capillary dimensions defining ink and air channels; said channels providing communication between the ink and air channels of the cutting element and the space in communication with the ink and air channels of the feed-bar of the writing assembly.

20 4. In a fountain pen, the combination of a barrel, a writing assembly comprising a nib, a feed-bar having channels for the passage of ink and air and a sleeve in which said nib and feed-bar are permanently mounted to function as a unit detachably mounted in the end of the barrel, an ink-containing cartridge having a rupturable diaphragm sealing one end and disposed in the barrel opposite the writing assembly unit, and an ink-feeding assembly interposed between the writing assembly and the delivery end of the cartridge; said ink-feeding assembly comprising a body member having a through bore in axial alignment with the cartridge, a tubular cutting element carried by and disposed in the bore of said body member and adapted to pierce the diaphragm of the cartridge when the parts are assembled, means arranged

25 5. In a fountain pen, the combination of a barrel, a writing assembly comprising a nib, a feed-bar having channels for the passage of ink and air and a sleeve in which said nib and feed-bar are permanently mounted to function as a unit detachably mounted in the end of the barrel, an ink-containing cartridge having a rupturable diaphragm sealing one end and disposed in the barrel opposite the writing assembly unit, and an ink-feeding assembly interposed between the writing assembly and the delivery end of the cartridge; said ink-feeding assembly comprising a body member having a through bore in axial alignment with the cartridge, a tubular cutting element carried by and disposed in the bore of said body member and adapted to pierce the diaphragm of the cartridge when the parts are assembled, means arranged

30 6. In a fountain pen, the combination of a barrel, a writing assembly comprising a nib, a feed-bar having channels for the passage of ink and air and a sleeve in which said nib and feed-bar are permanently mounted to function as a unit detachably mounted in the end of the barrel, an ink-containing cartridge having a rupturable diaphragm sealing one end and disposed in the barrel opposite the writing assembly unit, and an ink-feeding assembly interposed between the writing assembly and the delivery end of the cartridge; said ink-feeding assembly comprising a body member having a through bore in axial alignment with the cartridge, a tubular cutting element carried by and disposed in the bore of said body member and adapted to pierce the diaphragm of the cartridge when the parts are assembled, means arranged

35 7. In a fountain pen, the combination of a barrel, a writing assembly comprising a nib, a feed-bar having channels for the passage of ink and air and a sleeve in which said nib and feed-bar are permanently mounted to function as a unit detachably mounted in the end of the barrel, an ink-containing cartridge having a rupturable diaphragm sealing one end and disposed in the barrel opposite the writing assembly unit, and an ink-feeding assembly interposed between the writing assembly and the delivery end of the cartridge; said ink-feeding assembly comprising a body member having a through bore in axial alignment with the cartridge, a tubular cutting element carried by and disposed in the bore of said body member and adapted to pierce the diaphragm of the cartridge when the parts are assembled, means arranged
